UNITED STATES PATENT OFFICE.

HERBERT McNULTA, OF CHICAGO, ILLINOIS.

PASSENGER-CAR FOR RAILWAYS.

1,035,216.

Specification of Letters Patent. Patented Aug. 13, 1912.

Application filed June 28, 1909. Serial No. 504,651.

To all whom it may concern:

Be it known that I, HERBERT McNULTA, a citizen of the United States, and a resident of Chicago, in the county of Cook and State 5 of Illinois, have invented certain new and useful Improvements in Passenger-Cars for Railways, of which the following is a full, clear, and exact specification.

This invention relates generally to improvements in passenger cars for railways, 10 more particularly to that type commonly known as trolley or street cars, and especially to that type of cars known as side or center entrance cars.

15 The prime object of my invention is to avoid the necessity of any step structure or steps between the ground and the car platform, and to have the entrances to and the exits from the car so arranged that passengers may simultaneously, without obstructing each other, enter and pass therefrom, and do so without traversing more than half the length of the car, and to provide means whereby the ease of entering and leaving 20 the car is substantially promoted, the exertion of the passenger therefor materially lessened and the time consumed thereby reduced to a minimum.

Another object of my invention is a passenger car the entrances and exits and the platform of which are so arranged that it is 30 for the first time practicable to truss the car structure with diagonal truss members located above the line of window rails or sills 35 without annoyingly obstructing the view of passengers, and to construct the side frames in a truss of greater relative depth than heretofore constructed; whereby the weight of passenger cars of the same general dimensions may be substantially reduced 40 without impairing their strength, durability or appearance, and whereby the power necessary to propel them may be correspondingly reduced.

45 A further object of my invention is to provide means by which all passengers entering and passing from a stepless car are at all times directly in front of and in close proximity to the conductor when standing 50 in a position convenient for receiving fares and for carrying out his duties in connection with the operation of the car, and whereby the motorman or driver of the car is entirely relieved of any responsibility for 55 or interference by such passengers.

Another and important object of my in-

vention is a stepless car, the entrances and exits of which are so arranged as to provide for a substantial increase in the number of seats in a car of given length, as compared 60 with end platform cars.

Another important object of my invention is an arrangement of entrances and exits of a passenger car providing for floor spaces to be occupied by standing passengers, near 65 the entrances and exits, and thereby readily available to them.

A further object of my invention is to provide a novel arrangement of gates or doors at the entrance and exit of the car 70 platform, so that the side of the platform may be closed or opened and so that on a center platform car either side of the car may be open and the other side closed by one set of doors or gates shifted by the conductor 75 without leaving the platform.

A still further object of my invention is to provide in a passenger car having either end or center platforms and having separate entrance and exit passages for passengers, 80 doors or gates to the compartments of the car, novel in construction and operation within convenient reach of the conductor from the position he will usually occupy 85 when the car is in operation, and which can be easily manipulated by passengers entering or leaving the compartments; the novel arrangement of these doors being such as to permit the construction of the platforms of end or center platform cars with platform 90 center or intermediate sills or supports substantially integral with or continuations of the center or intermediate sills of the car body, and clear of the truck wheels and motors when such truck wheels or motors are 95 located so closely to the platform that they will barely clear the outside platform sills or knees.

A further object of my invention is to have the trolley pole of an electric car in 100 such an arrangement relatively to the car body that the plane inclosing the trolley pole will be so nearly tangent to the overhead wire on curves at the point of contact of the trolley wheel or shoe with the wire 105 that the liability of the wheel or shoe to leave the wire at a curve is reduced to a minimum, and the wear on both wheel and wire reduced; and an arrangement whereby the trolley rope is within convenient reach 110 of and under the control of the conductor standing on the center platform with the

passengers entering and passing therefrom directly in front of him.

Still another and important object of my invention is a passenger car, the entrances and exits of which are arranged relatively to the body thereof, and the platforms so constructed that a triple decked or floored car may be produced by adding a deck or floor above the dropped center floor or platform, with a minimum increase in the height of the car whereby the triple decked car may pass through tunnels and under bridges and into car house doors which, owing to their restricted height, are impossible of passage by double decked cars as heretofore constructed, whether with a roof over the upper deck or without a roof, and having passengers standing upright thereon. The construction by which the triple decked car is made possible with minimum height is such that the trucks may be separated toward the end of the car as far as clearance for the car on curves will permit, allowing seats for a considerable number of passengers on the platform deck who will therefore traverse no steps, and allowing a material increase in the floor space and in seats for passengers on the upper deck located nearer the ground than on double decked cars as heretofore constructed, with but slight increase in the weight of the car over that of a single decked car. In addition for a subway or underground car this construction permits several separate entrances and exits on both lower and upper decks, so that passengers may enter and leave at two levels, or again passengers may enter at one level and leave at the other, thus facilitating loading and unloading, and reducing the interference between entering and leaving passengers.

With these ends in view, my invention finds embodiment in certain features of novelty in the construction, combination and arrangement of parts by which the said objects and certain other objects hereinafter appearing are obtained; as fully described with reference to the accompanying drawings and more particularly pointed out in the claims.

In said drawings:—Figure 1 illustrates in side elevation a trolley car embodying a part of my invention. Fig. 2 is a plan view in horizontal section on line *a*—*b* of Fig. 1. Fig. 3 is a vertical cross section of the same car on line *c*—*d* of Fig. 1. Fig. 4 shows a side elevation of a triple decked car embodying a part of my invention. Fig. 5 is a plan view in horizontal section of the car shown in Fig. 4, that portion to the left of the line 15—16 being a section at line 17—18 of Fig. 4, and that portion to the right of line 15, 16 being a section on the line 19—20 of Fig. 4. Fig. 6 is a plan of the platform of the car shown in Fig. 1, showing the cen-

tral portion of Fig. 2 on an enlarged scale and in more detail. Figs. 7, 8 and 9 are plan views in horizontal section through the doors of several arrangements of non-reversible doors between the platform and the compartment of a car. Fig. 10 is a plan view in horizontal section of an arrangement of reversible compartment doors, being a modification of the arrangement shown in Figs. 3 and 6. Fig. 11 is a plan view in horizontal section of the compartment doors shown in Fig. 10, and illustrates the position of parts during the operation of reversing the doors. Fig. 12 is a plan view of the roof of a trolley car showing the arrangement of the trolley pole with reference to the body of the car which embodies a part of my invention.

In passenger cars as heretofore constructed the floor or the platform has been at such height that one or more exterior steps have been constructed by which the passenger mounts to the floor or platform from the ground or track level, street cars requiring one or more steps, so called inter-urban and steam railway passenger cars requiring two or more steps. In practice these steps are of greater individual rise than is common in ordinary stairways, so that the exertion required of the passenger is greater than if the same height were reached by steps of less individual rise. Also the larger the individual rise and the larger the number of steps in continuous flight the greater the exertion required and the time consumed by the passenger in making a safe and secure entrance to or exit from the car. To reduce the exertion and time required by the passenger to enter or to leave the car, and to make the entrance and exit more safe and secure, a part of my invention is embodied in a stepless car having a portion of its floor or its platform lowered to or constructed at a level that it may be mounted directly from the ground by the passenger taking one step, such floor or platform extending across the car preferably from sill to sill, and communicating with the main floor of the car located over the trucks and wheels by means of an inclined plane or of but few steps of convenient, and preferably of easy rise and tread, said steps being at a substantial distance from the point of entrance to the platform.

In the accompanying drawings in which like figures indicate like parts a portion of the floor or the platform 21 is located at a height from the ground or from the top of the rail 22 that it may be mounted by the passenger taking one step, and extends across the car from outside sill 23 to outside sill 24, its length longitudinally of the car being such as may be desired within the limits imposed by clearance for the trucks 25. Steps or stairs 26, 27 lead from the plat-

form 21 to the main floor or seating compartment 28. In Figs. 1, 2 and 3 a car is illustrated having an entrance passage 29 continuous with the platform 21 but separated from the exit passages 30, 30 by the vertical posts 31, 31 and the hand rails 32, 32 attached to posts 31, 31. The passenger boards the car at passage 29, passes across the platform 21 in view of the conductor 10 facing him at 33, behind the railing 34, mounts the steps 26 and enters the compartment 28 through the door 35. The passenger when leaving the car passes from the compartment 28 through the door 36 down the steps 27 through the exit passage 30, at the level of the platform 21, and to the ground with a single step of the foot. The doors 35 and 36 may be located respectively at the top or bottom of the steps 26 and 27.

20 The car illustrated in Figs. 4 and 5 has the passage 29 on the platform 21, and the door 35 and steps 26 serving for both entering and leaving passengers. In both the cars illustrated in the drawings the steps 26 25 and the steps 26^a mounted by entering passengers are located at a substantial distance from the entrance passage 29, and may be of easy rise so that the exertion made and time consumed by the passenger in making 30 a safe entrance to the platform 21 is less than if there were external steps to the platform, and the exertion in reaching the compartment 28 from the ground is less than in cars as commonly constructed with steps of 35 much greater individual rise than is ordinarily used in other step constructions, such as for stairways in buildings.

The rise of steps in dwellings and in other buildings seldom exceed eight inches, 40 whereas the rise of steps to passenger cars is seldom as small as eight inches, and in some cases exceeds thirteen inches, the larger rise being used on cars for reducing the number of steps required to reach the floor of the 45 car from the ground so as to occupy the least amount of horizontal space, and give width to the platform. With the construction embodied in my invention of interior steps from the platform 21 to the main floor 50 28 the number of steps may be increased and therefore their individual rise reduced to reach the floor 28 from the ground 29 over that in the usual construction, and the width of the platform retained to extend 55 from sill to sill because the platform 21 is below the interior steps 26, 26^a and 27.

It is obvious that my construction shown in the drawings as applied to a side or center entrance car may be used on end 60 platform cars, the platform 21 extending from outside platform sill to outside platform sill across the car and steps 26 and 27 arranged for entering and leaving the compartment 28, but I have preferred to show 65 my invention applied to side or center en-

trance cars since this and other features embodied in my invention are especially adapted to a side or center entrance car, and that furthermore some of these features are impossible without or in the absence of side 70 or center entrances.

I am aware that passenger cars have been constructed with end platforms having separate entrance and exit passages on each platform from the ground to the platform 75 and between the platform and the compartment of the car, and that side or center entrance cars have been constructed with separate entrance and exit passages from the ground to the platform, but I do not know 80 of side or center entrance cars having been constructed with separate entrance and exit passages from the ground to the platform on either or both sides of the car and having at the same time separate entrance and exit 85 passages from the platform to the compartments of the car; nor do I know of any side or center entrance car having been constructed with the platform at such entrance located at a level below the level of the main 90 floor of the car.

My invention herein described of a stepless platform or floor with the platform extending the full width of the car at its sills enables a side or center entrance car 95 to have for the first time separate entrance and exit passages from the ground to the platform, on either or both sides of the car, and at the same time separate entrance and exit passages to the compartments from the platform. In Figs. 1, 2 and 6 entrance passage 29 and exit passages 30, 30, separated by the vertical post 31, and the hand rails 32, are shown at one side of the platform 21 with doors 56 and 57 inclosing the other side 100 of the platform, so that passengers may enter and leave at but one side of the car; and there are shown also steps 26 and doors 35 separate from steps 27 and doors 36 connecting the platform 21 to the compartments 105 28. By removing the hand rails 32 and the platform inclosing doors 56, 57, both sides of the car will be open for the ingress and 110 egress of passengers. It is customary however to have but one side of a car open for 115 the ingress and egress of passengers, and with my arrangement either side of the car at will may be open without having duplicate devices and having separate entrance 120 passages 29 and exit passages 30, 30 to the platform 21, and separate entrance doors 35 and exit doors 36 between the platform 21 and the compartments 28, and the other side 125 closed. Figs. 1 and 2 show the right side of the platform 21 open and the left side closed by the doors 56, 57, the direction of 130 operation of the car being to the right hand in the drawings as shown by the position of the trolley pole 87 in Fig. 1. By shifting the position of the doors 56 and 57 from the

left hand to the right hand side, by means hereinafter disclosed, and by shifting the hand rails 32, separating the entrance passage from the exit passages, from the right hand side of the platform 21 to the left hand side in similar but reversed position, and connecting the post 31 to the guards 69 on the left hand side, the arrangement of the entrance and exit passages is reversed from that shown in the drawings. Furthermore, in passenger cars as heretofore constructed it has not been possible to construct the side framing in the form of a truss of which the diagonal members extended above the level of the window rails or sills without such diagonal members crossing the windows and annoyingly obstructing the view of the passengers. Passenger cars commonly known as side or center entrance cars by reason of the entrances being located between the trucks and at some distance from the ends of the car, but not necessarily at the exact center, have been constructed with two or more steps between the ground and the car platform, this construction necessitating the cutting away of the sills, if of wood, or of their being bent in a horizontal or vertical plane and reinforced if of metal, in either case requiring additional material either in the side sills or in intermediate or center sills to obtain the requisite strength. Furthermore, these side entrance cars have had platforms and outside steps so short longitudinally of the car that diagonal truss members, above the window rails or sills, would pass across so many windows as to annoyingly obstruct the view of a large number of passengers. My invention, however, embodies an arrangement of parts by which a side or center entrance car may be constructed with the side framing of wood or of metal in the form of a truss whose diagonal members may pass above the line of window rails or sills, in some cases without being located across the windows in the side of the car as shown in Fig. 4, and not crossing more than two windows at each side of the entrance as shown in Fig. 1; this construction being made possible by reason of the low platform or floor 21 which may extend so close to the trucks 25 that few, if any, of the windows opening above the main floor 28 will be crossed by diagonal truss members, and that the diagonal truss members will pass above the tops of the window openings located over the platform or floor 21.

In the drawings Figs. 1 and 4, by reason of the platform 21 being located below the level of the main floor 28, the sills 23 are bent or built up so that the portion 37 lies at or below the level of the platform 21, and below the portions 38 of the sills 23 which extend over the trucks 25; the portions 39 of the sills 23 being formed of separate

pieces or by bends in the sills 23. The portions 39 are extended at 40, and with the portions 37 and 40 form the lower chord of a truss suspended over the truck centers 41, through the posts 42, the car body bolsters 43, the other members of the truss being the platform corner post 44, the window posts 45, the window rails 46, extensions 47 of the portions 38 of the sills 23, the girders 48, the lintel 49 of the side doors, such lintel being extended if necessary, of the diagonal struts or compression members 50, 50, and of such other members as may be necessary or desirable. The struts 50 are extended to 51 and joined to the portion 38 of sills 23 to support the overhang of the car beyond the body bolster 43, the posts 52 and the diagonal members 53 (see Fig. 1) being used to strengthen the overhang. In Fig. 1 the diagonal members 50 cross the window openings 54, but the view of passengers through these windows will not be annoyingly obstructed because, as will be seen, in Fig. 2, the seats 55 are arranged longitudinally so that the backs of passengers seated thereon will be toward the windows 54, 54. When, however, the floor or compartment 28 extends a shorter distance from the body bolster 43 toward the platform 21 than in the car shown in Figs. 1 and 2, the diagonal members 50, as shown in Fig. 4, will pass clear of the window openings 54, 54. Since the center platform 21, with one entrance passage 29 and two exit passages 30, 30 occupies less longitudinal space in the car than would two end platforms each having one entrance passage and one exit passage of the same length longitudinally of the car as on the center platform, and since in a center platform car the space corresponding to that occupied on one of the end platforms of a car by the motorman may be utilized for seats, the seating capacity of a center platform car is greater than that of an end platform car of like over all dimensions. In addition, the center platform car with longitudinal seats arranged near the entrances and seats, as shown at 55, 55, (see Figs. 2 and 6) has the advantage, as compared with an end platform car, having longitudinal seats arranged near the platforms, that the open standing spaces between the longitudinal seats 55, 55 are located in close proximity to both of the entrances and to both of the exits of the compartment and of the car, whereas on an end platform car only one of these spaces is in close proximity to the rear platform, which is commonly used as the only entering point to the car; with the result that these standing spaces may be more easily occupied by passengers than on end platform cars in which entering passengers traverse nearly the entire length of the compartment to reach the forward standing space, which

they are loath to do when the car is crowded because of the difficulty of reaching the forward standing space.

In passenger cars as heretofore constructed of that type having doors or gates inclosing the sides of the car platform, a set of doors or gates is provided at each edge of the platform which are hinged to the posts and to one another for folding into a space of small compass, or which are slid longitudinally inside or outside of the side of the compartment of the car, for the purpose of opening the sides of the platform for the ingress or egress of passengers. Such hinged or folding doors interfere more or less with passengers, and such sliding doors necessitate such construction in the side framing of the car, and occupy so much space inside or outside of it that the clear inside width of the car is reduced so that the seats located therein are crowded nearer together than would be the case were such sliding doors not in use.

A novel arrangement of the side inclosing doors or gates for a car platform is embodied in my invention consisting of doors or gates, sliding or folding together if necessary to clear obstacles that may obstruct their passage across the platform, and of means for transferring them across the platform consisting of overhead rails extending from side to side of the car over the platform, on which slides or wheels carry the doors or gates. By this arrangement the doors or gates are entirely removed from that side of the platform in use by passengers, and hence do not interfere with them, and they need not be sub-divided into a large number of sections to fold into a small compass. For a car on which either one or the other of its sides is to be always open and the other side closed only one set of doors or gates is required.

In Figs. 1, 2, 3 and 6, the folding doors 56, 57, of such width when folded together that they will pass the guard 69 while being swung across the platform 21, are suspended from the rollers 83 (see Fig. 3) which travel across the platform on the overhead rails 84, the rails 84 having inclined surfaces near the sides of the car at 85, 85, by means of which the rollers 83 will quickly rise and lift the lower edges of the doors 56, 57 clear of the floor of the platform 21, in starting the shift of position of the doors, and will, at the opposite side, lower the doors to the platform 21. It is obvious that this arrangement for transferring the doors 56, 57 from side to side of the platform is applicable to an end platform car as well as to a side or center entrance car.

Heretofore the door openings or passages have commonly been constructed between the platform and the compartment of a passenger car substantially crosswise or at

right angles to the length of the car. I am aware that single door openings have been constructed diagonally or at an oblique angle with the length of the car in the interior structure of it for the purpose of changing the direction of, or the location of, a passage from the side toward the center of the car longitudinally, or for the purpose of communicating with some interior sub-division of the compartment, but I do not know of passenger cars being constructed with two door openings or passages between the platform and the compartment set diagonally or at an oblique angle with the length of the car, and converging toward the platform.

Embodying in my invention are novel arrangements of the separate entrance and exit door or gate openings and novel doors or gates between the platform of a car and its compartment, applicable to end platform cars as well as to side or center entrance cars, the main feature of which is that a pair of doors or gates are located with the planes of their openings diagonal to the longitudinal vertical center plane of the car and converging toward the platform.

In the several figures of the drawings, excepting Figs. 4, 5, and 12, the pair of doors 35, 36, located between the platform 21 and the compartment or main floor 28, have their openings which the doors 35 and 36, normally close, extending between the post 60 (see Fig. 7) and the posts 59, or between the posts 60 (see Figs. 8 and 9) and the fixed center post 58, or between the post 60 and the center door posts 66 (shown in Figs. 2, 3, 6, 10 and 11) said posts 66 being revolute. The planes of these door openings or the planes of the doors when normally closed lie diagonally to a vertical center plane passing longitudinally through the car, and these planes converge toward the platform 21; the purpose being that, with a given width of opening between the posts 60 and the posts 58, 59 or 66, the posts 60 will be farther from the outside platform corner post 44 than if the posts 58, 59 or 66 and the post 60 were set in line with the post 44, and the openings thus substantially crosswise or at right angles to the longitudinal center line of the car. The results are that the passenger entering or leaving the compartment 28 is directed more nearly toward the longitudinal center plane of the car and farther away from passengers seated in the seats 55 than if the door openings of equal width were located crosswise; that more space is inclosed in the compartment 28 without loss of useful space on the platform than if the openings were located crosswise; and that, in either end platform or side entrance cars in which the trucks 25 (Fig. 1) are located close to the platform 21 or to the body end sill 62 (Figs. 7 and 8),

130

- center or intermediate platform sills substantially integral with or continuations of the body center or intermediate sills 63 (Figs. 7 and 8) may be used to support the platform 5 form by bending them downward between the body end sill 62 and the door posts 58, 59 or 66, which platform sills could not be used integral with or continuations of the body center or intermediate sill 63 in cars in which the door openings were crosswise and located over the body end sill 62 because the bend in the platform center sills would interfere with the trucks or wheels when the car passed around curves.
- 10 In Fig. 7 the doors 35 and 36 are shown as sliding telescopic doors operating in the usual manner to close against the post 59, so spread from the longitudinal center line of the car as to form with the center post 20 58 a space 52a on the platform, in which space the conductor may be located.

In Fig. 8 another arrangement is shown in which the sliding doors 35 and 36, operating in the usual manner, close upon the center door post 58, thus bringing the doors 25 35 and 36 and their openings more nearly toward the center of the car, and giving greater clearance to passengers seated on the seats 55, 55 from passengers entering 30 and leaving the car than as shown in Fig. 7.

In Fig. 9 an arrangement is shown similar to that in Fig. 8, except that door 36 at the right hand of Fig. 9 is a swinging door shown as swinging outward, though if desired it may swing in either direction: and in this connection it should also be stated that all of the doors 35 and 36 may be similar swinging doors.

A novel arrangement of the pair of doors 40 35 and 36, embodying a part of my invention, is illustrated in Figs. 1, 2, 3, 6, 10 and 11, in which a sliding door 35, hung from the usual rollers 64 (Fig. 3), traveling on the usual rails 65 (Fig. 3) is carried by the 45 vertical post 66 to which the rail 65 and its braces 67 (Fig. 3) are fixed. The vertical post 66, shown in the drawings as a channel section, carries also the swinging door 36, whose hinges 68, fitted with springs for retaining the door 36 normally in one position, are fixed to the post 66. The post 66 is pivoted at its top at 73 and at its bottom at 74 in suitable bearings, such as shown in Fig. 50 8, so as to be free to turn, carrying with it the doors 35 and 36; the purpose being the use of the sliding door 35 for entering the compartment 28, from the platform 21, and of the swinging door 36 for passing from the compartment 28 to the platform 21, the 55 positions of the doors 35 and 36 relative to the platform 21 and to the compartment 28 being reversible by revolving the post 66 about its pivot 73, 74 so that whichever side of the car is open for the ingress and egress 60 of passengers, the doors 35 and 36 may be

placed in proper relation thereto, which is accomplished by swinging the doors 35 and 36 in the direction indicated by the arrows in the left hand portion of Fig. 6, and as indicated by the arrows in Fig. 11, until the hinged door 36 occupies the position indicated by the dotted lines in the left of Fig. 6 and the door 35 occupies the position indicated by dotted lines at the left and below the center line of Fig. 6. The sliding door 75 35, normally closed against one or the other outer door posts 60, on being opened slides inwardly and diagonally toward the center of the car and over the platform 21, and is provided with guards 69. (Figs. 3 and 6) 80 consisting of wire screens or glazed partitions, or other suitable materials, to prevent persons on the platform 21 being struck by the sliding door 35 while it is being moved to an open position. The swinging door 36 85 swings closely to and may pass both the outer door posts 60, and is normally held close to one or the other of the posts 60 by the tension of its spring hinges 68 against the stop 70 (Figs. 2 and 6) or against the button 71 (Figs. 10 and 11) so that it may be normally opened outwardly only toward the platform 21. The post 66 is held by a hook 101 (see Fig. 3) or by any other suitable locking device in either of the two positions at which the doors 35 and 36 will normally close the openings between the posts 60 and the post 66, in the arrangement shown in Figs. 1, 2, 3 and 6. The position of the doors 35 and 36 are reversed by first 90 releasing the hook 101, then partially opening door 35 clear of post 60 and pulling the door 35 outwardly toward the platform 21. The post 66 is thereby revolved until the door 35 is in the line in which it will slide 95 into its closed position on that side of the post 66 opposite to that from which it was swung. At the beginning of this operation the door 36 will be against the stop 70 as shown in Figs. 2 and 6, and the stop 70 is 100 permanently fixed to the post 60 so that the door 36 may be normally closed against the stop 70 to form a weatherproof joint. In order to shift the position of the door 36 105 from one door opening to the other by the method of operation previously described, the door 36 must pass inwardly and swing through the compartment 28. In order that the door 36 may pass the stop 70 the pivot line of its hinges at 72 in Fig. 6 is set eccentric to the axis of the pivots 73 and 74 of the posts 66, so that as the posts 66 revolves about its pivots 73, 74, the pivot line 72 of the hinges 68 of the door 36 will be so 110 moved that the door 36 will be withdrawn from the stop 70, and will then, by the tension of its spring hinges 68, swing around into compartment 28 toward its new position. As soon as the door 36 is clear of the stop 70 the movement of the door 35 and 115

120

125

130

of the post 66 is discontinued and the door 36 is then manually drawn against the tension of its spring hinges through the opening to which it is being shifted and behind 5 the stop 70 on the post 60 against which it will close when in its new position, and the movement of the door 35 and of the post 66 is then continued until the door 35 is in proper position to be slid into its new position 10 covering the opening previously occupied by the door 36. The hook 101 is engaged to lock the post 66 in its reversed position thus completing the operation of reversing the doors 35 and 36.

15 For the purpose of reducing the number of operations required to shift the positions of the doors 35 and 36, as previously described, and to reduce the number of guards 69 from two to one, I have shown in Figs. 20 10 and 11 a modified arrangement for shifting the above described positions of the doors 35 and 36, and this arrangement is the one I prefer. The sliding door 35 and the 25 swinging door 36 are mounted, as previously described, on the pivoted post 66, except that the door 36 has its pivot line 72 through the hinges 68 coincident with the axis of the pivots 73 and 74 of the posts 66, as shown in Figs. 10 and 11. The buttons 71, capable 30 of being turned out of the path of movement of the door 36 and mounted on the posts 60, are substituted for the permanent stops 70 in Fig. 6, and there is but one guard 69 for the sliding door 35, this guard 69 being pivoted at 75 and carrying fixed to it a gear 76 whose center coincides with the axis of the pivot 75. The gear 76 meshes with a gear 77 fixed to the pivoted post 66 with its axis coincident with the axis of the pivots 73 40 and 74 of the posts 66. I do not limit myself to the use of the gears 76 and 77 herein described for giving a simultaneous motion in opposite directions of the guard 69 and the posts 66, as there are other means of accomplishing the same results, for example 45 by levers, or by crossed chain belting. The guard 69 has attached to it hand rails 78 (Figs. 10 and 11) and has hinged to it at 79 (Fig. 11) the hand rail 32 whose function is 50 to separate the entrance passages and the exit passages on the platform 21 as shown in Figs. 2 and 6, and which is attached to the vertical post 31, 31 (Fig. 3) by any suitable latch here shown as a tongue 102 formed at 55 the end of hand rail 32 held in the jaw 103 fixed to the post 31 by the pin 104 passing through the tongue 102 and the jaw 103. The guard 69 is provided also with a bolt 80 sliding up and down on the outer edge of 60 the guard 69 and fitting into the sockets 81 and 82 let into the floor of the platform 21, its purpose being to securely hold the guard 69 and therefore the doors 35 and 36 in one or the other of their normal positions during 65 the operation of the car. There are

other locking devices in ordinary use which will perform the functions of the bolts 80 and the sockets 81 and 82. In the arrangement of parts as described and as shown in Fig. 10, the doors are in their normal position for operation, the sliding door 35 on the left, and the swinging door 36 on the right, the door 36 being prevented from opening inwardly by the button 71. The entrance 29 and the exit 30 of the platform 21 are at the right of Fig. 10. To reverse this arrangement so that the entrance passage 29 and the exit passage 30 on the platform 21 may be to the left, and so that the door 35 may be on the right, and the door 36 on the left, the buttons 71 are turned to permit the door 36 to pass them, the sliding door 35 is partly open to clear the post 60, the hand rail 32 is unfastened from the post 31 by removing the pin 104 from the jaw 103 (Fig. 3), and the bolt 80 is drawn up from the socket 81. The hand rail 32 is swung to the left on the hinge 79, the guard 69 is then swung to the left about the pivot 75, the gears 76 and 77 thereby revolving the post 66 with the attached doors 35 and 36 in a direction that the door 35 moves outwardly toward the platform 21, and when one half of the movement is completed the position will be as shown in Fig. 11 and the direction of motion as indicated by the arrows in Fig. 11. Continuing the movement of guard 69 until the bolt 80 registers with socket 82, locking it therein, closing door 35 to the right, turning the button 71 at the left behind the door 36 now on the left of post 66, and fastening the hand rail 32 to the vertical post 31 at the left side of the platform 21 completes the reversal of the doors 35 and 36 and of the entrance and exit 90 95 100 105 110 115 120 125 130 passages 29, 30 on the platform 21 from the right to the left side.

Heretofore on that type of electric cars known as trolley cars by reason of the electric current being taken from an overhead conductor by means of a contact or trolley wheel attached to the end of a trolley pole, the trolley pole has been mounted on the roof of the car with its vertical pivot, around which the pole swings in order that the contact or wheel may follow the conductor on curves, located to the rear, with reference to the direction of travel of the car, of a vertical line passing through the center of the forward axle of a single truck car or passing through the center pin of the forward truck of a double truck car. The vertical pivot has been commonly so located that the pole may be manipulated from the rear end of the car by means of a rope attached to it at its upper end near the contact or wheel, and in practice, because of the relative lengths of the trolley poles and of the overhang of the car in the rear of the trucks, the vertical pivot has been located

forward of a vertical line through the center of the rear axle of a single truck car or through the center pin of the rear truck of a double truck car; with the result that the 5 trolley pole is never tangent to the overhead conductor when the car is on a curve, and there is, therefore, a tendency for the contact or wheel to leave the wire or conductor on curves, and for the wheel and conductor to wear more rapidly than if the pole were tangent to the curves in the conductor.

Referring to Fig. 12 in which the line 105 is the intersection of the longitudinal center 15 vertical plane through the car with its roof, the arrow indicating the direction of travel of the car, the lines 106 and 107 are the intersections of vertical transverse planes through the car respectively with the centers of the front and rear axles of a single 20 truck car, or with the center pins of the front and rear truck of a double truck car. The overhead conductor is indicated by the curved line 108, though in actual practice 25 the conductor will, if a wire, form chords to the curve herein indicating the trolley wire located at 108, whose radius is 109. For the purposes of this description it is assumed 30 that the curve 108 lies vertically over a similar curve representing the center line of the track on which the car operates, which assumption is closely but not absolutely correct in actual practice. It is therefore also assumed that the points 110 and 111 at the 35 intersections respectively of the line 106 and the line 107 on the line 105 located above the centers of the axles of a single truck car or above the center pins of a double truck car will follow very closely the curve 108 as the 40 car passes around the curve. If the vertical pivot of the trolley pole is located at any point between points 110 and 111, as for instance at point 112, the trolley pole 87, shown in horizontal projection as the line 45 113 contacts with the curved line 108 at the point 114, and is not tangent thereto. The vertical pivot of the trolley pole 87 may be located at two points on the line 105, at which points 115 and 116 the trolley pole of 50 a given length and with a given distance between the roof of the car and the overhead conductor will be tangent to the curve 108 at the point of contact with it, and these two points are the only points at which this will 55 occur. As shown in the drawing in Fig. 12, if the vertical pivot for the trolley pole is located at the point 116 on the rear end of the car so as to be tangent to the curve 108, its swing from the vertical center plane of the 60 car indicated by line 105 is much greater than if the vertical pivot were located at the forward end of the car at point 115, the pole being shown in horizontal projection at 65 117. The dotted curved line 118 represents 65 the center line of a curve in the track and in

the overhead conductor similar to that shown by line 108, but of different radius, and the line 119 is a horizontal projection of the trolley pole 87 pivoted at the point 115 and contacting with the curve 118 and 70 tangent thereto.

The arrangement embodied in my invention consists in locating the vertical pivot 86 (in Figs. 1 and 4) for the trolley pole 87 forward of the vertical transverse plane 75 passing through the center line of the forward axle of the single truck car or through the center pin of the forward truck of the double truck car in such position that the center line of the vertical pivot 86 will coincide with the line formed by the intersection of two planes perpendicular to the car floor, the one parallel to the longitudinal center line of the car, the other passing through the center line of the trolley pole 85 and tangent at the point of contact of the trolley shoe or wheel with the overhead conductor to the curve in the overhead conductor, or to that curve of which the overhead conductor forms chords, the vertical 90 lines through the vertical pivot for the trolley pole being located at point 115, (Fig. 12) previously described. With this arrangement the trolley pole 87 will be very closely tangent to all curves in the overhead conductor and the side swing of the pole will be a minimum and so small in practice that the rope 98 (see Fig. 1) may pass through a slot or other opening 99 in the roof of the car and be manipulated at the inside of the car 100 or on the center platform 21 by the conductor standing thereon, who will have the pole 87 in view through glass plates set in the trap doors 100, forming a portion of the roof 105 of the car.

Heretofore passenger cars and other vehicles have been constructed, commonly known as double decked by reason of having a seating compartment on the roof of the usual compartment reached by a ladder 110 or by stairs leading from one or both end platforms of the vehicle. Such stairs, being constructed to occupy the least possible amount of space on the platform, were so narrow and of such steep incline that they 115 were difficult to mount. Heretofore these double decked cars for railways have been constructed with the upper deck located over a continuous lower or main floor extending over the truck wheels, so that when loaded 120 the center of gravity of the car and its load was at a considerable height, the distance from the ground to the upper floor or deck was considerable, and the height of the car 125 such that the roof of the upper deck or the heads of standing passengers, if there were no roof, would not in a large number of instances clear obstructions such as tunnels, overhead bridges and car house doors. Therefore the use of such cars has been lim- 130

ited to situations as have either no over-head obstructions or such obstructions of sufficient height to permit the car to make a clear passage. A large number of railways have a clear height between the track and overhead obstructions sufficient for the safe passage of locomotives and cars having a maximum of height of fifteen feet. The minimum diameter of wheels in common 10 use for steam railway cars and for the motor driven axles of electric cars is thirty inches, and therefore the lower floor of a double deck car, if constructed as heretofore with such floor continuous over the truck wheels, 15 will not be less than three feet above the track level. Allowing a clear height for passengers of six feet six inches on each of the two floors of such a car and five inches for the thickness of roof and of the upper 20 floor, the total height of the car from the ground comes to sixteen feet five inches, so that it is impossible, using proper wheels and proper clearances for passengers, to construct a double decked car by the methods 25 heretofore used that will pass under obstructions already existing on a larger number of railways.

In connection with my invention hereinbefore described of a stepless car with a 30 platform or floor constructed below the level of the main floor, the latter passing over the trucks, it becomes possible to construct an upper deck or floor above the dropped floor or platform, forming what I have 35 herein termed a triple deck car, which consists, as shown in Figs. 4 and 5, of a platform deck 21 without external steps, located at a lower level than the main deck or floor 28, which latter is constructed at a 40 level above the trucks and wheels 25, and of a third or upper deck 90, located above and extending approximately the full length of the lower deck 21. Seats 91 are arranged on the lower deck 21. Stairs 26* 45 of easy rise and wide tread lead from the lower deck 21 to the main deck 28, and stairs 92 of comfortable width, of easy rise and of broad tread, and in broken flight lead from the main deck 28 to the upper 50 deck 90, on which are arranged the seats 93 under cover of the permanent roof 94 and inclosed by the cab 95. With a height of one foot five inches from the track level to the top of floor 21, six feet six inches clear 55 head room between the lower deck 21 and the upper deck 90, six feet eight inches clear head roof between the upper deck 90 and the underside of roof 94, three inches depth of floor 90 and two inches depth of roof 60 94, the total height of the car from the track level to the top of the roof is fifteen feet. It thus becomes possible by reason of the low height of platform 21 from the track level 22 to construct a car with an 65 upper deck 90 that will pass through a

large number of tunnels, under a large number of bridges and through a large number of car house doors that are already constructed and that may hereafter be constructed with clearances that are standard, 70 with a large number of railways; that will have a comparatively low center of gravity when loaded; that will seat a considerable number of passengers on its lower deck who will take but one step to mount or dismount 75 from the car; that will have its main floor 28 reached by steps 26* of easy rise and wide tread; that will have its upper floor 90 located nearer the ground level 22 and nearer 80 the level of the main floor 28 than in cars as heretofore constructed, so that the upper floor may be more easily reached by the passengers; and that will have steps 92 of comfortable breadth, easy rise and wide tread leading to its upper floor 90. 85

By reference to Figs. 4 and 5 it is evident that if the trucks 25, 25 are farther separated from one another toward the ends of the car, the length of the lower deck 21, and hence also the length of the upper deck 90 90 may be increased so that a larger number of passengers may be carried by a car of given length by reason of the increase in the length of the upper deck 90. It is further evident by reference to Figs. 4 and 5 95 that more doors may be constructed on either or both sides of the lower deck 21, and that if desired doors may be constructed opening into the upper deck 90 at 97 or at any other convenient point, by which with suitably constructed station platforms passengers may enter and leave the cars at two levels or may enter at one level and leave at another, which features are especially applicable to sub-way or underground cars 100 since passengers occupying the upper compartment or deck 90 would traverse a minimum distance between the surface of the ground above and the deck 90 of the car, though passengers occupying the lower deck 105 21 would traverse a slightly greater distance than is now customary with the floor of a single deck sub-way car at the level of the main floor 28. In any case with the large number of doors possible by this construction and by having them distributed at two different levels, the loading and unloading of passengers will be much facilitated. 110

Having described my invention, what I claim and desire to secure by Letters Patent 120 of the United States is:—

1. A railway passenger car comprising in combination a car floor, car sills forming supports for said floor, drop bends between the ends of said sills, a platform supported 125 from the bends of said sills and extending from sill to sill in a plane below that of the car floor, substantially as described.

2. A railway passenger car comprising in combination a car floor, side sills for the 130

car provided with drop bends at a point intermediate the ends of said sills, a platform and means for supporting said platform adjacent said drop bends the entire width of the car in a plane substantially below the car floor, and steps leading from said platform to said floor whereby passengers may, with a single upward step upon the platform, pass entirely across the car before taking 10 their seats, and on reaching the platform from their seats pass to the ground by a single short step, substantially as described.

3. A railway passenger car comprising in combination a car floor, side sills extending 15 from end to end of the car each of which is provided at substantially its center of length with a depression projecting below the plane of the car floor terminating at each side thereof, and a platform extending from side 20 sill to side sill adjacent said bends and in a plane below the car floor, substantially as described.

4. A railway passenger car comprising in combination side sills extending the length 25 of the car provided with central bends projecting below the floor of the car, a platform supported by said bent portion below the plane of said floor, diagonal strut members secured to the side sills near their free ends 30 and inclining thence upwardly to near the top of the car body, and side openings in the car at a point between the apex of the strut members and the bends of the side sills for the exit and entrance of passengers, sub- 35 substantially as described.

5. A railway passenger car comprising in combination side sills therefor provided at about their center of length with depressed 40 portions, a platform extending from side to side of the car, and means for supporting the same adjacent said bent portions in a plane below the car floor, diagonal struts, the respective apices of which are located above the center of length of said bent portions 45 and well toward the top of the sides of the car, and chord members connecting the bent portions of the sills with said struts, substantially as described.

6. A railway passenger car comprising in combination side sills extending substantially 50 the length of the car body, provided with depressed angular bent portions, diagonal struts, the outer ends of which are secured toward the ends of said sills with 55 their apices terminating well toward the top of the sides of the car and substantially at the center of length of said sides, diagonal

chord members connecting the bends of the side sills with the strut member, and an opening in the side of the car between the apices of the strut members and the bottom portion of the bend in the side sills, substantially as described.

7. A railway passenger car comprising in combination side sills therefor provided with depressed portions about their center of length projecting in a plane below the floor of the car and adapted for directly supporting a platform extending from side sill to side sill in a plane therewith, an entrance 65 and exit passage to said platform, windows in both sides of said car extending from said entrance to both ends of the car with their bottom portion in the same plane, diagonal struts the apices of which are located directly above said entrance passage and extending thence across but two windows on each side of said passage and with their ends secured to the side sills well toward each end thereof whereby the view of the occupants 70 of the car is not annoyingly obstructed and trussed side frames are provided of maximum depth whereby the weight of the car is substantially reduced without impairing its strength, durability or appearance, with 75 minimum annoyance to its occupants, substantially as described.

8. A railway passenger car comprising in combination side sills provided with a drop or bent portion at a point intermediate the 80 length thereof, a platform extending between said bent portions of the side sills and entirely in a plane below the floor of the car, and direct entrances in the side of the car to both sides of said platform, a number of 85 windows on each side of said entrances, the bottom portions of which are in the same plane, a diagonal strut the ends of which are secured to said side sills toward the ends thereof, the apices of which struts terminate 90 immediately above said entrances, and diagonal truss chord members secured at their upper ends to the struts in a plane below the bases of said windows with their lower ends secured to the side sills at a point bisecting 95 the line of the bends projecting downwardly therefrom, substantially as described.

In witness whereof, I have hereunto set my hand and affixed my seal, this 8th day of May A. D. 1909.
